UNITED STATES PATENT OFFICE.

WINFIELD A. GIVEN, OF FREEPORT, MAINE.

LAPSEAM BLUCHER TONGUE.

Application filed January 30, 1926. Serial No. 84,874.

This invention relates to shoes of the so-called blucher type and more particularly to a shoe of this type having a bellows tongue. The sole and vamp of such a shoe are usually constructed of rubber or other waterproofed materials, and the upper of leather or like materials.

In this type of shoe, especially when made for outing or hunting purposes, the tongue and upper are so shaped and attached to each other that near their edges there is defined a row through which eyelets are inserted, the shoe being fastened by a shoe lacing threaded through these eyelets. In the usual construction, just below the eyelet row and above the point where the upper is attached to the vamp, there is a relatively short space where the union of the tongue and upper is not reinforced except by a single stitching of the parts together. Obviously this is a weak point in the construction of the shoe, and, as it happens, this is also one of the points in the shoe which receives greatest wear as it lies over the foot just at the turn of the ankle.

This weakness has been recognized for years and various attempts have been made to devise methods and means to relieve this wear or to reinforce the shoe at this point. These means have consisted in patches, stay strips and other reinforcing pieces of many shapes and styles. In spite of these improvements, however, it remains the fact that this point in a blucher type hunting shoe is one of the first to show wear and break. The most common way of fastening the tongue to the upper now in use in the trade is simply to stitch the tongue and quarter to each other. Any breaking of the stitching destroys the waterproof nature of the shoe and may materially injure the whole article.

To overcome these difficulties, I have devised my present invention. I have introduced no new parts into the shoe or added materially to the labor or time required to produce the finished article. I have, however, so designed these familiar parts and devised a method of joining them to each other that the finished article is greatly improved and strengthened at just this point which requires reinforcement.

I have disclosed in the drawings and described in the specification a practical embodiment of my invention, the details of which will be completely set forth in the

specification which follows. Similar reference numerals are used to indicate corresponding parts in the drawings and specification. In the drawings:

Fig. 1 is a view of a finished shoe constructed in accordance with my invention.

Fig. 2 is a view of the tongue member.

Fig. 3 is a fragmentary view showing the reinforcing flap and one method of attaching the same to the shoe.

Fig. 4 shows three sections illustrating different steps in attaching the tongue and flap to the shoe.

Fig. 5 is a section over the line 5—5 of Fig. 3.

Fig. 6 is a fragmentary view of an upper showing a reinforced strip of somewhat different construction.

Fig. 7 is a fragmentary view of the tongue adapted to be joined to the quarter shown in Fig. 6.

Fig. 8 is a view of Figs. 6 and 7 united.

Fig. 9 shows sections illustrating the different steps in uniting this quarter and tongue.

Fig. 10 is a section on the line 10—10 of Fig. 8.

Fig. 11 is a view of an upper and tongue either or both of which may have a flap like that shown in Figs. 1 to 5 inclusive, the same however flying loose.

Fig. 11^a shows the flap lying outside of the upper, and

Fig. 11^b is a view showing a flap both inside and outside of the shoe.

A shoe constructed in accordance with my invention consists of the usual quarter 1, tongue 2 and vamp 3 which is usually constructed of rubber.

The inner faces of the tongue 2 and the quarter 1 are joined together to form an eyelet strip 4 through which eyelets 5 are inserted.

In the form of my invention disclosed in Figs. 1 to 5, inclusive, the tongue 2 has near its lower edge lateral flaps 6.

In the form of my invention shown in Figs. 6 to 10 inclusive, the quarter 1 is provided with a similar tab 7.

In the form shown in Figs. 11, 11^a and 11^b, one or more tabs are provided as desired.

Heretofore neither the tongue nor the upper has been provided with reinforcing tabs and the two edges thereof have simply

been stitched together by a single row of stitching. This is but a relatively weak seam and one which frequently comes apart when subjected to wear.

5 Referring first to the construction shown in Figs. 1 to 5, the quarter 1 and tongue 2 are united to each other in the usual manner, the rows of stitching 9 and 10 defining the eyelet strip 4 (Fig. 1).

10 In Fig. 4 I have illustrated the three steps required to completely unite the flap, which in this case is integral with the tongue, to the upper.

The row of stitching 9 on the outer edge 15 of the eyelet row 4 is carried down to fasten the tongue 2 and quarter 1 to each other below the eyelet row just back of the tab 6 as shown at 10. In order to make this union doubly strong, the work is turned in

20 the machine at the lower edge of the tongue and the quarter, and a second row of stitching 11 put through the tongue and quarter as near as possible at the same point occupied by the row 10, the row 11 being continued above the point where the flap is joined to form the inside stitching of the eyelet row 4.

At this step, the tab 6 extends outwardly 30 beyond the rows of stitching 10 and 11. I next open and flatten out the tongue 2 and quarter 1, which were held face to face while the stitchings 10 and 11 were being inserted, so that the tab 6 will overlie and can be 35 stitched to the quarter 1 as indicated at 12 in the third step shown in Fig. 4. This third row of stitching 12 as shown in Figs. 1 and 3, is continued about the entire outer edge of the tab 6 so that the same is closely and neatly united to the upper 1.

40 It will be noted that in this case the flap overlaps the stitchings 10 and 11 and is attached to the upper 1 by what is usually referred to as a lap seam. This gives the strongest possible union of the parts and I believe satisfactorily overcomes the difficulties and weaknesses heretofore encountered at this point in a shoe of this type.

Referring to the form disclosed in Figs. 6 to 10 inclusive, it will be noted that in 50 this case a reinforcing tab extends laterally adjacent the lower edge of the quarter instead of from the tongue as in the form hereinbefore referred to. In this case the first rows of stitching 13 and 14 join the tongue 55 and the quarter in the same manner as do the rows of stitching 10 and 11 (see Figs. 3 and 4). In this case, however, the row of stitching 15 which corresponds to the row 12 does not lie inside of the seam formed by the rows 13 and 14, but appears as a 60 third row of stitching through the quarter and tongue back of the tab 7, the same however being continued about the edges of the said tab to join the same to the tongue as 65 shown in Fig. 10.

In Figs. 11, 11^a and 11^b, I have shown another possible embodiment of my invention. In this form, there may be tabs 16 and 17 on both shoe and quarter. If this form of reinforcement is used, part of the stitching 70 operation may be omitted, it being possible only to unite the quarter and tongue by a single row of stitching 18 at just about the point where the lateral tabs 16 and 17 project. If desired, these tabs may be stitched 75 to their respective tongue and quarter, or the flap on the inside of the shoe need not be fastened but may lie loose against the inside of the shoe as shown in Fig. 11^a. If preferred, but one tab may be provided and 80 this may be stitched along its outer edges to the tongue or quarter or allowed to fly loose as desired. In Fig. 11^b tabs are shown on both upper and tongue and both are lying loose. In any event, whether the tab is 85 stitched to the shoe in the very complete and certain manner disclosed in Figs. 1 to 10 inclusive, or is attached at one or two points as shown in Figs. 11 to 11^b, any one of these is a considerable improvement over the 90 old butted seam heretofore used.

Various changes in the positioning of the reinforcing tabs or in the arrangement or numbers of rows of stitching may obviously be made without departing from the spirit 95 of my invention if within the limits of the appended claims.

I claim:

1. In a shoe, an upper including a blucher type quarter and a bellows tongue, said 100 quarter and tongue being stitched to each other, and a lateral reinforcing tab on one of said members and attached to the other member in lapseam construction.

2. In a shoe, an upper including a blucher 105 type quarter and a bellows tongue, said quarter and tongue being stitched to each other to form an eyelet row and a lateral reinforcing tab on one of said members below said eyelet row and attached to the other 110 member in lapseam construction.

3. In a shoe, an upper including a shaped quarter and a correspondingly shaped tongue a lateral reinforcing tab on one of said members, said quarter and tongue being stitched 115 to each other to define an eyelet row, said stitching being carried below said eyelet row through said quarter and tongue back of said reinforcing tab, and said tab being folded over upon said stitching in lapseam 120 construction, and stitched to the member of which it is not an integral part.

4. In a shoe upper, a blucher type quarter and a tongue united to the forward edge of said quarter, said tongue having adjacent 125 its lower edge an integral reinforcing flap, said flap being turned back on said quarter and stitched thereto by a lapseam.

5. In a shoe upper, a blucher type quarter and a tongue united to the forward edge 130

of said quarter by a double row of stitching to define an eyelet row, said tongue having below said eyelet row, and laterally adjacent its lower edge, a reinforcing flap, the 5 row of stitching uniting said quarter and said tongue and defining said eyelet row, being continued to join said tongue to said upper just back of said flap, said flap being folded over upon said rows of stitching 10 and again stitched to said quarter to form a lapseam.

6. In shoe construction, an upper structure including a quarter and a tongue marginally stitched to each other to form an 15 eyelet row, a reinforcing tab extending laterally from one of said members and overlying the other of said members, and stitched thereto by a line of stitching which passes through both of said members and which ex- 20 tends substantially as a continuation of the

line of stitching which marginally secures the upper and tongue to each other.

7. In shoe construction, an upper structure including a quarter and a tongue marginally stitched to each other to form an 25 eyelet row, a reinforcing tab extending laterally from one of said members and overlying the other of said members and stitched thereto by a line of stitching which passes through both of said members and which ex- 30 tends substantially as a continuation of the line of stitching which marginally secures the upper and tongue to each other, said tab beyond said stitch line being additionally stitched to the underlying member only 35 of the upper structure by an independent line of stitching constituting with the first-named line of stitching a lapseam.

In testimony whereof I affix my signature.
WINFIELD A. GIVEN.
